UNITED STATES PATENT OFFICE.

GENNARO GIUGLIANO, OF WEST HOBOKEN, NEW JERSEY.

HOLDER FOR A PAPER OF PINS.

1,038,345.

Specification of Letters Patent. Patented Sept. 10, 1912.

Application filed June 21, 1911. Serial No. 634,465.

To all whom it may concern:

Be it known that I, GENNARO GIUGLIANO, a citizen of the United States, and a resident of West Hoboken, in the county of 5 Hudson and State of New Jersey, have invented a new and Improved Holder for a Paper of Pins, of which the following is a full, clear, and exact description.

The object of the invention is to provide 10 a new and improved holder for holding a paper of pins, and arranged to display a single row of pins at a time and in such a manner that the individual pins of the displayed row of pins can be readily removed 15 by the user whenever desired.

A practical embodiment of the invention is represented in the accompanying drawings forming a part of this specification, in which similar characters of reference indicate 20 corresponding parts in all the views.

Figure 1 is a perspective view of the holder for a paper of pins and arranged in the form of a stand; Fig. 2 is a transverse section of the holder hung up on a wall; 25 and Fig. 3 is a perspective view of the winding-up roller with the movable member in open position.

A suitably constructed casing A is provided at its front upper portion with a door 30 B connected at its lower end by hinges C with the fixed lower portion of the front D of the casing A, and the said door is provided at the sides near the upper end with fastening devices E for holding the door B 35 in a closed position. When the door B is unlocked and swung into an open position then a paper of pins can be conveniently placed in the casing A, it being understood that the paper of pins consists of the usual 40 sheet of paper F, on which are held rows of pins F'.

In the open top of the casing A extends a fixed bar G, over which is adapted to pass a sheet of paper F, the said bar G being arranged 45 relative to the upper free end of the door B, so that the row of pins F' on the top at the time extends from the bar G to and below the free end of the door B, so as to hold the paper of pins against movement 50 over the bar G in a rearward direction, as will be readily understood by reference to Fig. 2.

It is understood that by the arrangement

described the row of pins F' in uppermost position at the time is readily displayed for 55 convenient removal of the individual pins of this uppermost row by the user of the holder, and when the pins of the uppermost row have all been removed from the sheet of paper F, then the latter can be drawn 60 over the bar G in a rearward direction to draw up the next following row of pins into uppermost position and to display the same for convenient removal of the individual pins by the user as previously mentioned. The empty portion of the sheet of 65 paper F winds on a drum or roller H journaled in the sides of the casing A a distance below the bar G and approximately opposite the lower ends of the pins F' of the 70 uppermost row of pins. The roller or drum H is provided at its ends with knobs H' extending outside of the casing A, to permit the user to wind up the sheet of paper F after the pins F' of the uppermost row of 75 pins have been removed. The drum or roller H is preferably provided with a hinged clamping member H² to permit of clamping the terminal of the sheet of paper F between the parts so as to permit of 80 readily winding up the sheet of paper F on the drum H.

The casing A may be arranged in the form of a stand for supporting it on a table or the like, and for this purpose the casing 85 is preferably provided with a lug I pivoted at I' on the sides of the casing A, and adapted to rest on the table or other support, as plainly indicated in Fig. 1. The lug I is provided at its sides with a flanged 90 extension I² for attachment to a wall or other support as indicated in Fig. 2, and the casing is also provided at its back and at the upper end thereof with a loop J for engagement with a pin K driven into a wall 95 or other support.

A pincushion L is preferably mounted on the front of the lug I, which latter is also provided with a drawer N for storing miscellaneous articles.

Having thus described my invention, I claim as new and desire to secure by Letters Patent:

In a holder for a paper of pins, a casing having an open top and provided with a 105 hinged door at its front upper portion,

means in the casing for exposing a row of a
paper of pins at the open top of the casing,
and a supporting member pivoted to the
ends of the casing and extending forwardly
5 beyond the front of the casing and adapted
to rest upon a table or other support.

In testimony whereof I have signed my

name to this specification in the presence of
two subscribing witnesses.

GENNARO GIUGLIANO.
